Patented Dec. 16, 1919.

.INVENTOR

LYLE K. SNELL

BY ATTORNEY

UNITED STATES PATENT OFFICE.

LYLE K. SNELL, OF DETROIT, MICHIGAN, ASSIGNOR TO CADILLAC MOTOR CAR COMPANY, OF DETROIT, MICHIGAN, A CORPORATION OF MICHIGAN.

MOTOR-VEHICLE.

1,324,853.

Specification of Letters Patent.

Patented Dec. 16, 1919.

Application filed March 2, 1917. Serial No. 151,886.

To all whom it may concern:

Be it known that I, LYLE K. SNELL, a citizen of the United States, and resident of Detroit, Wayne county, State of Michigan, have invented certain new and useful Improvements in Motor-Vehicles, of which the following is a specification.

This invention relates to improvements in motor vehicles and more particularly to 10 spring oilers therefor.

One of the objects of the invention is to devise an efficient lubricator of simple construction which may be readily applied to a vehicle spring.

15 Another object of the invention is to devise a lubricator for vehicle springs which shall be practically dust proof.

Another object of the invention is to provide a lubricator which shall clamp the several leaves of the spring against lateral movement.

20 Another object of the invention is to provide a spring lubricator which may contain an abundant supply of lubricant and which shall be of durable construction and of neat appearance.

The various objects, purposes, constructions and principles involved, will more clearly appear from the following description, taken in connection with the accompanying drawings which form a part of this specification and in which:

Figure 1, is a side elevation of a section of a vehicle spring showing a form of the 35 invention applied thereto.

Fig. 2, is an enlarged transverse vertical sectional view on the line 2—2, Fig. 1.

Fig. 3, is a vertical longitudinal sectional view on the line 3—3, Fig. 2.

40 Fig. 4, is an enlarged view looking at the under-side of a section of the spring having the invention applied thereto.

Fig. 5, is a side elevation of a portion of a spring curved in the reverse direction to that shown in Fig. 1, and showing a modified form of the invention applied thereto.

Fig. 6, is an enlarged transverse vertical sectional view on the line 6—6, Fig. 5.

Fig. 7, is a longitudinal vertical sectional 50 view on the line 7—7, Fig. 6.

Fig. 8, is an enlarged view showing the underside of a section of a spring with the modified form of the invention applied thereto.

Referring to the drawings, particularly 55 Figs. 1 to 4, inclusive, 10 illustrates a portion of a section of an upwardly curved laminated leaf spring, the leaves of which are adapted to be secured together by the arrangement midway between the ends of a 60 shackle plate 11, and bolts, 12.

Lubricating devices which will be presently more particularly described may be suitably arranged on the spring at opposite sides of the shackle.

65 Each of the lubricating devices comprises a U shape casing member 13, preferably stamped or forged out of sheet steel. The casing member is adapted to have struck up or formed therein intermediate its width, a 70 passage or channel 14, extending from one extremity to the other.

A deflector plate 15 is adapted to be arranged across the bottom of the channel 14, in the transverse portion or top 17, of the 75 casing member, with its opposite edges 18, adjacent the top of the side channels 19, which are formed in the downwardly extending branches 20 of the casing member. The deflector plate 15, may be suitably secured in position in the casing member as 80 by welding.

The casing member is adapted to be arranged over and slipped downwardly into position over a section of the spring 10. It 85 will be noted that a port 21 is formed in the top 17, and an oil reservoir 22, is provided with a cap 23, and is adapted to be secured over this port, as by threads 24. The member 13 is provided with flanged portions 90 25, which are adapted to extend parallel to the adjacent edges and surfaces of the various portions of the spring on which it is mounted. An absorbent material, such as in the form of wicks 26, may be arranged between the sides 27, of the spring leaves and the outer wall of the channel 19.

The casing member 13 may be secured in position against lateral or longitudinal movement relative to the spring leaves, by means 100 of a plate 28, which is adapted to extend across the entire bottom of the casing member 13, and to be secured to the bottom leaf 29 of the spring as by a rivet 30. The opposite ends of the plate 28, may be struck up to 105 form a pair of bosses 31, and bolts 32 may be passed through lugs 33 formed at the lower extremities of the branches 20 of the mem-

ber 13, and through the bosses 31 in the plate 28 for securing all of these parts in position.

It will be observed that a slight clearance 5 is maintained between the surface of the upper leaf of the spring and the interior of the top 17 of the member 13 for permitting a limited up and down movement of the springs relative to the casing member and 10 prevent binding therebetween.

Referring particularly to Figs. 5 and 8 inclusive, it will be noted that a modified form of oiling device is shown applied to a downwardly curved section of a laminated leaf 15 spring. The general form of the casing member of this spring device is very similar to that described in connection with the other figures; it, however, being arranged on the spring in reverse relation to that of the 20 previously described device.

It will also be noted that the modified form of casing member 13' is not provided with a port in its transversely extending portion; the oil reservoir in the modified 25 construction is arranged at the opposite end of the casing member.

A plate 28' having down turned ends forming bosses 31' is adapted to be arranged across the upper extremities of the branches 30' of the casing member 13' for closing the entire upper portion of this member. Suitably arranged between the bosses 31' of the plate 28' and in spaced relation thereto, is a deflector plate 15'. A spacing collar 35 may 35 be inserted between plates 28' and 15' and these parts may be secured in position by a rivet 36 passing through the upper leaf of the spring and these two plates and the spacing collar. A pair of bolts 32, and their 40 complementary nuts connect the branches 20' of the casing member with the bosses 31' of the plates 28'.

It will be noted that the plate 28' is formed with port 21' over which is secured 45 the reservoir 22'.

With the latter described construction, lubricant is fed through the port 21' over the deflector plate 15' to the absorbent material 26, and any surplus oil which is not suspended by the wick will be collected in the reservoir 37 which is formed in the bottom 50 of the member 13'.

While I have described and will specifically claim what I deem to be a preferred 55 embodiment of my invention, it will be obvious to those skilled in the art that various modifications and changes may be made without departing from the spirit and scope thereof.

Having thus described my invention, what 60 I claim and desire to secure by Letters Patent is:-

1. An oiling device for multiple leaf 65 springs comprising a U-shaped casing having a centrally disposed channel, and two

flanges located one upon each side of said channel; a plate extending between the free ends of said casing and having two hollow bosses located one at each end thereof; two fastening bolts extending through holes provided in said flanges and through said bosses; two absorbent members located opposite one another and within the portions of the channel aforesaid which is in the sides of said U-shaped casing; and means for supplying a lubricating material to said absorbent members. 70 75

2. An oiling device for multiple leaf springs comprising a U-shaped casing having a centrally disposed channel, and two 80 flanges located one upon each side of said channel; a plate extending between the free ends of said casing and having two hollow bosses located one at each end thereof; two fastening bolts extending through holes provided in said flanges and through said bosses; two absorbent members located opposite one another and within the portions of the channel aforesaid which is in the sides of said U-shaped casing; a plate extending 85 across the portion of said channel which is in the part of said casing which connects the sides thereof with one another; and means for supplying a lubricating material to said absorbent members. 90 95

3. An oiling device for multiple leaf springs comprising a U-shaped casing having a centrally disposed channel, and two flanges located one upon each side of said channel; a plate extending between the free 100 ends of said casing and having two hollow bosses located one at each end thereof, and projecting portions between said bosses and extending into said channels and closing the ends thereof at the free ends of said casing; two fastening bolts extending through holes provided in said flanges and through said bosses; two absorbent members located opposite one another and within the portions of the channel aforesaid which is in the sides 105 of said U-shaped casing; and means for supplying a lubricating material to said absorbent members. 110

4. An oiling device for multiple leaf springs comprising a U-shaped casing having a centrally disposed channel, and two flanges located one upon each side of said channel; a plate extending between the free ends of said casing and having two hollow bosses located one at each end thereof, and projecting portions between said bosses and extending into said channels and closing the ends thereof at the free ends of said casing; two fastening bolts extending through holes provided in said flanges and through said bosses; two absorbent members located opposite one another and within the portions of the channel aforesaid which is in the sides of said U-shaped casing; a plate extending 120 across the portion of said channel which is 125 130

in the part of said casing which connects the sides thereof with one another, and which plate closes the open side of the channel aforesaid; and means for supplying a lubricant to the portion of said channel within the connecting portion of said casing.

5. The combination with a multiple leaf vehicle spring, of a casing substantially **U** shaped and fitted flat around three sides of said spring intermediate of the length thereof and having a center depression forming a channel therearound and an oil feed opening communicating therewith, a bottom plate extending across said spring between the ends 10 of said frame and having the opposite edges thereof rolled to form orifices, shackle bolts extending through said orifices and the ends of said casing and clamping the same against said spring, a wick filling in said channel at each side of said spring and a cover plate secured in said casing on the upper side of said spring and forming a passage with said channel opposite side oil feed opening.

15. The combination with a multiple leaf vehicle spring, of a casing substantially **U** shaped and fitted flat around three sides of said spring intermediate of the length thereof and having a center depression forming a channel therearound and an oil feed opening communicating therewith, a bottom plate 20 at each side of said spring.

6. The combination with a multiple leaf vehicle spring, of a casing substantially **U** shaped and fitted flat around three sides of said spring intermediate of the length thereof and having a center depression forming a channel therearound and an oil feed opening communicating therewith, a bottom plate 25

extending across said spring between the ends of said frame and having the opposite edges thereof rolled to form orifices, shackle bolts extending through said orifices and the ends of said casing and clamping the same against said spring, a wick filling in said channel at each side of said spring and a cover plate secured in said casing on the upper side of said spring and forming a passage with said channel opposite side oil feed opening.

7. An oiling device for multiple leaf springs comprising a **U** shaped casing 40 formed with a central channel depression extending therearound and lugs at the extremities thereof, shackle bolts extending through said lugs and securing the ends of said casing together, a plate rolled at opposite edges 45 thereof, around said shackle bolts and completing the fourth side of said casing, a cover plate secured to said casing and forming therewith a passage communicating with the channel on each side thereof, a wick filling 50 in each side channel and an oil cup having communicating means with said passage.

In testimony whereof I affix my signature.
LYLE K. SNELL.
